(57) CLAIM

I claim the ornamental design for a turtle shaped bongo drum, as shown and described.

DESCRIPTION

FIG. 1 is a left side perspective view of a turtle shaped bongo drum showing my new design;

FIG. 2 is a front elevational view thereof;

FIG. 3 is a left side rear elevational view thereof;

FIG. 4 is a rear elevational view thereof;

FIG. 5 is a top view thereof; and,

FIG. 6 is a bottom view thereof.
